B. D. POWELL

SPOOL AND THIMBLE RACK

Filed April 16, 1921

UNITED STATES PATENT OFFICE.

BUREN D. POWELL, OF KOSSE, TEXAS.

SPOOL AND THIMBLE RACK.

Application filed April 16, 1921. Serial No. 461,815.

To all whom it may concern:

Be it known that I, BUREN D. POWELL, a citizen of the United States, residing at Kosse, in the county of Limestone and State 5 of Texas, have invented certain new and useful Improvements in a Spool and Thimble Rack; and I do hereby declare the following to be a full, clear, and exact description of the invention, such as will enable others 10 skilled in the art to which it appertains to make and use the same.

The object of the invention is to provide a simple, inexpensive and efficient device for supporting spools and thimbles and like 15 objects either for the convenience of the seamstress or trade display, and incidentally to provide means in connection therewith whereby a needle cushion may be suspended within convenient reach, and with this object 20 in view the invention consists in a construction and combination of parts of which a preferred embodiment is shown in the accompanying drawing, wherein:

Figure 1 is a view of a rack embodying 25 the invention.

Figure 2 is a vertical sectional view of the same.

Figure 3 is a plan view of the blank from 30 which the rack is formed.

The device consists essentially of a base 35 plate 10 carrying a plurality of outstanding fingers 11 which are preferably cross sectionally round or tubular to constitute convenient means upon which may be threaded and supported such articles as spools 12, thimbles 13 and the like, said plate, for example being provided at its upper corner with an eye or opening 15 for engagement with a supporting hook 16 or the equivalent 40 thereof, and being provided at its lower corner with a hook or ear 17 upon which may be suspended any convenient or preferred article such as a needle cushion or the like.

45 The device is preferably struck from a

single blank of sheet metal as indicated in Figure 3, with flaps 18 separated from the body of the sheet or blank at their upper and side edges to form openings 18' and said flaps being rolled to form the spool and 50 thimble supporting fingers. This construction not only economizes in the material required for the device but serves to minimize the weight thereof without detracting in any way from the strength of the same, and 55 in addition the finger blank being integral with the plate or main blank requires no fastening means, and by cutting the lower edges of the flaps on upwardly convergent lines as indicated at 19, the lower ends of the 60 rolled flaps forming the fingers are beveled to maintain the fingers at the proper upward inclination with relation to the plane of the base as indicated clearly in Figure 2. The 65 fingers are thus braced against downward deflection which would tend to render them less effective in supporting the objects engaged therewith.

Having thus described the invention, what 70 I claim is:—

A rack having a base plate and flaps struck therefrom to form supporting fingers, each flap formed by cutting the base plate in substantially rectangular form, the base 75 of the form being cut converging to form re-entrant angles at either side, said cuts being spaced apart, the flap so formed being bent down away from the base plate and the side edges rolled to abutting position by bending in same downward direction that 80 the sides of base of said flaps will engage base plate to maintain the fingers in position inclined upwardly from base plate.

In testimony whereof I affix my signature in presence of two witnesses.

BUREN D. POWELL.

Witnesses:

R. S. POWELL,
Mrs. J. S. POWELL.
